UNITED STATES PATENT OFFICE.

HARRY D. COWDEN, OF PITTSBURG, KANSAS.

MOP.

1,420,525.

Specification of Letters Patent. Patented June 20, 1922.

Application filed September 2, 1921. Serial No. 497,849.

To all whom it may concern:

Be it known that I, HARRY D. COWDEN, a citizen of the United States, residing at Pittsburg, in the county of Crawford and State of Kansas, have invented certain new and useful Improvements in Mops, of which the following is a specification.

This invention relates to mops and it comprises a mop head formed of a single piece 10 of wire or similar material having loops or eyes formed on opposite sides, handle securing means adapted to be received in said loops, and a mop comprising a casing adapted to fit over the mop head, the top of the 15 casing being provided with openings for the passage of the loops.

An object of the present invention is the provision of a mop head formed of a single piece of wire which will be relatively inexpensive to manufacture.

A further object is the provision of a mop having a casing for the reception of the mop head.

A further object is the provision of means 25 for securing the handle to the mop, the handle securing means being further adapted to assist in retaining the mop on the mop head.

In the accompanying drawings, I have 30 shown one embodiment of the invention. In this showing:

Figure 1 is a perspective view of a mop head and mop in assembled position,

Figure 2 is a similar view of the casing 35 forming a portion of the mop,

Figure 3 is a detail view of the mop head,

Figure 4 is a detail sectional view of a portion of the mop and mop head, and,

Figure 5 is a side elevation of a portion 40 of the handle.

Referring to the drawings, the reference numeral 1 designates generally a mop head formed of wire or other suitable material. The mop head may be made any desired 45 shape, and, as shown, it is formed triangular with a rear or base 2 and converging sides or arms 3. Arranged on each side of the mop head, and substantially equidistant from the base, there are provided loops 4 for the reception of the handle securing means. The handle securing means consists 50 or a piece of wire having offset ends

5 adapted to be received in the loops of the mop head. Beyond the ends, the wire is extended in a pair of converging arms 6 55 having coils or loops 7 formed therein to place the offset ends under tension and retain them in the loops. The central portion of the wire is coiled, as at 8, and is adapted to receive threads 9 formed on the end of a 60 handle 10.

The mop to be used with the mop head comprises a back or casing 11 substantially triangular in shape provided with an open base 12. The casing is arranged over the 65 mop head, as shown in Figure 4, the walls 13 being arranged one below and one above the wire frame. The base of the casing is provided with a snap fastener 14, adapted to engage a catch 15 to retain the casing in 70 position. The upper side of the casing is provided with suitable openings 16 for the passage of the loops 4. The threads 17 forming the mop are secured to the under side of the casing.

The method of using the mop will be clearly apparent from the foregoing description. In assembling, the mop head 1 is first inserted in the casing, the loops passed through the openings 16, and the fastener 14 secured. The offset ends 5 of the handle securing member are then inserted in the loops and the mop is ready for use. To disassemble the mop, the operation is 75 reversed.

The mop produced may be readily and quickly assembled and consists of very few parts, making it relatively inexpensive to manufacture and very unlikely to get out of order.

It is to be understood that the form of the invention herewith shown and described is to be taken as a preferred example of the same, and that various changes in the shape, size, and arrangement of parts may be resorted to without departing from the spirit of the invention or the scope of the subjoined claim.

Having thus described my invention, I 100 claim:

A mop comprising a casing formed of two pieces of fabric of substantially the same size and shape secured to each other along their edges, the two adjacent edges at

one side of the casing being free, said casing being provided with spaced openings on its upper side, a mop secured to said casing, a mop frame adapted to be received in said casing, said mop frame being provided with portions projecting through said openings, means for closing the free side of said casing, and a handle securing member detach-

ably engaging the projecting portions of said mop frame.

In testimony whereof I affix my signature in presence of two witnesses.

HARRY D. COWDEN.
